UNITED STATES PATENT OFFICE.

ARMAND H. PEYCKE, OF CHICAGO, ILLINOIS, ASSIGNOR TO THE AMERICAN STEEL
FOUNDRIES, OF CHICAGO, ILLINOIS, A CORPORATION OF NEW JERSEY.

METHOD OF FORMING BRAKE-BEAM FULCRUMS.

1,302,702.

Specification of Letters Patent.

Patented May 6, 1919.

Application filed January 28, 1918. Serial No. 214,101.

To all whom it may concern:

Be it known that I, ARMAND H. PEYCKE, a citizen of the United States, and resident of Chicago, in the county of Cook and State of Illinois, have invented certain new and useful Improvements in Methods of Forming Brake-Beam Fulcrums, of which the following is a specification.

This invention relates to brake beam fulcrums and more particularly to a method of forming same.

The main object of this invention is to simplify and improve the method of forming brake beam fulcrums and to increase the strength thereof.

Another object is to provide a brake beam fulcrum adapted to meet the various requirements for successful commercial operation.

Generally speaking, these and other objects are accomplished by providing a brake beam fulcrum by the use of the method consisting first in providing a blank having a lever receiving portion, then pressing another portion of the blank into a cross shape, and then expanding this cross shaped portion to increase the strength thereof.

The invention is illustrated on the accompanying sheet of drawings in which, Figure 1 is a plan view of a brake beam fulcrum formed in accordance with my invention;

Fig. 2 is a side elevation of the same showing the beam engaging lips out of their normal positions when fastened to a beam;

Fig. 3 is a sectional view taken in the plane of line 3—3 of Fig. 2;

Fig. 4 is a side elevation, and Fig. 5 is a plan view of the blank from which my brake beam fulcrum is formed;

Fig. 6 is a plan view of the brake beam fulcrum in a formative stage after the blank was bent intermediate its ends;

Fig. 7 is a side elevation of the arrangement shown in Fig. 6 and also showing an associated brake beam in section;

Fig. 8 is a plan view of the completed brake beam fulcrum after the same has been upset, and

Fig. 9 is a side elevation of the completed brake beam fulcrum applied to a brake beam shown in section.

The various novel features of my invention will be apparent from the following de-

scription and drawings and will be particularly pointed out in the appended claims.

In my improved method of forming a brake beam fulcrum, I make use of a single blank 15 which in one operation is stamped or drop forged from suitable stock and provided with a central elongated opening 16 and a circular opening 17 at each end of the blank. This blank, as shown in Figs. 4 and 5, after being heated to a welding heat is bent intermediate its ends adjacent the opening 16 into the shape shown in Figs. 6 and 7, the portions directly to the left of opening 18 as shown in Fig. 7 being welded together.

It will be understood that suitable dies are used in this operation, there being a suitable mandrel located at the bend to form alined openings 18 in the spaced walls 19 of the fulcrum. These spaced walls form a U-shaped recess or opening for the reception of a supporting member or brake lever. The ends of the blank are bent into a shape adapted to embrace a brake beam 20. The ends of the blanks, however, are not bent into the final position, as shown in Fig. 9, until it is desired to apply the same to the brake beam. The lever end of the blank is upset by suitable movable and stationary die members to the form shown in Figs. 8 and 9, wherein the side walls 19 are made narrower and with greater depth. The walls also during this operation are provided with outwardly or laterally extending bosses 21 which are provided with key notches 22 for locking in position a pin which may be extended through the openings 18 for connecting the fulcrum to a support or other member.

In order to strengthen the beam end of the fulcrum, this portion of the blank is then placed between dies which press the blank into a cross shape in section; that is, into a shape having radially extending ribs. In making this cross shape a shearing action at the beam end of the fulcrum is produced and in order to remove this internal shearing action a cone shape die is forced into the middle of the cross while a suitable die surrounds this portion of the blank, thereby removing all internal shearing strains. As a result of this last action, the beam end of the fulcrum has a conical internal wall 23 and a conical external wall 24 provided with a plurality of ribs 25, there being four in

this case, which converge toward the opposite end of the fulcrum and terminate in a circular connecting portion 26 of the side walls 19. After the conical die is driven into the rear portion of the blank, the beam embracing lips 28 are forced outwardly to the dotted line position shown in Fig. 2. When it is desired to apply the fulcrums to the brake beams, these lips are heated the desired amount and bent into a beam embracing position, as shown in Fig. 9. The fulcrum may be secured to the beam in any suitable manner. I have shown the fulcrum secured to the beam by means of a rivet 29 extending through the openings 17 which may pass through a registering opening in the beam.

By means of this method a forged brake beam fulcrum of maximum strength is provided by the distribution of metal hereinabove considered and which is adapted to meet the various requirements for successful commercial operation.

It is my intention to cover any modifications coming within the spirit and scope of the following claims.

I claim:

1. The method of forming a brake beam fulcrum, consisting first in providing a blank having a lever receiving portion, then pressing another portion of the blank into a cross shaped section, and then expanding this cross shaped portion to increase the strength thereof.

2. The method of forming a brake beam fulcrum, consisting first in providing a blank having a lever receiving portion, then pressing another portion of said blank to provide a plurality of ribs, and then expanding the ribs to increase the strength of the fulcrum.

3. The method of forming a brake beam fulcrum, consisting first in providing a

blank having a lever receiving portion, then pressing another portion of the blank to form ribs, and then expanding the ribbed portion to provide a recessed interior for increasing the strength of the fulcrum.

4. The method of forming a brake beam fulcrum, consisting first in providing a blank having a lever receiving portion, then pressing another portion of the blank into a form providing strengthening ribs, and then forcing the ribs outwardly to increase the strength of the fulcrum.

5. The method of forming a brake beam fulcrum consisting first in providing a blank having a lever receiving portion, then pressing another portion of the blank to form strengthening ribs, and then expanding said ribs outwardly by forming a conical recess for strengthening purposes.

6. The method of forming a brake beam fulcrum consisting first in providing a blank having a lever receiving portion, then pressing another portion of the blank to form strengthening ribs, and then expanding the ribbed portion to have internal and external conical surfaces for increasing the strength of the fulcrum.

7. The method of forming a brake beam fulcrum consisting first in providing a blank having a lever receiving portion, and then radially expanding another portion of the blank to increase the strength thereof.

8. The method of forming a brake beam fulcrum consisting first in providing a blank having a lever receiving fulcrum, and then expanding another portion of the blank outwardly to form an interior recessed portion for increasing the strength of the fulcrum.

Signed at Chicago, Illinois, this 22nd day of January, A. D. 1918.

ARMAND H. PEYCKE.
